UNITED STATES PATENT OFFICE.

SUMNER A. BEMIS, OF SPRINGFIELD, MASSACHUSETTS.

CABLE-CAR TRUCK.

SPECIFICATION forming part of Letters Patent No. 388,811, dated September 4, 1888.

Application filed May 1, 1888. Serial No. 272,474. (No model.)

To all whom it may concern:

Be it known that I, SUMNER A. BEMIS, a citizen of the United States, residing at Springfield, in the county of Hampden and State of Massachusetts, have invented new and useful Improvements in Car-Trucks, of which the following is a specification.

This invention relates to cable-car trucks, the object being to provide in cars of this class improved pivoting mechanism between the car and the truck, whereby the latter is permitted to swing in a horizontal plane under the car-body in passing around curves, the invention being in the nature of an improvement upon my patent of November 1, 1887, No. 372,293, to which reference may be had.

In the drawings forming part of this specification, Figure 1 is a plan view of a car-truck having car-pivoting devices attached thereto embodying my improvements, said figure having indicated thereon in dotted lines the outline and position of a portion of the floor-frame of a car and friction-rollers on said frame located opposite the sides of a pivot-ring on the truck. Fig. 2 is a section of Fig. 1 on line *x x* in that figure, showing a portion of the car-truck and of the floor of the car.

In my patent above referred to the cylindrically-shaped center-bearing constituting the "pivot-ring," so to speak, of the construction therein shown, consists of two separate segmental parts, each attached to the floor-timbers of the car, and having their lower ends pending beneath the same, the said pending ends entering a frame on the truck.

The object of this invention is to improve the pivoting mechanism between the truck and the car, as hereinafter described, thereby simplifying the same and making it stronger and more capable of resisting the strain upon said pivot parts when cable-cars are run at high speeds around curves.

In the drawings, 2 indicates the truck-frame, ordinarily of iron, which is hung upon the journals of the axles 3 through the intermediary of the usual axle-boxes, 4. To said truck-frame 2 are secured by their ends two transverse parallel trusses, 5, extending in lines with said axles, and to said trusses 5 are

secured by their ends two parallel shorter trusses, 6, at right angles to said trusses 5. To the upper sides of said trusses 5 and 6 are rigidly bolted by one end a series of metal clips, 7, to whose upwardly-projecting ends the continuous pivot-ring 8 (preferably of wrought-iron) is bolted, and is thereby supported with its sides in a vertical plane, as shown. The said ring supporting clips 7 have their upstanding ends bolted to the inner side of said ring in order to leave its exterior surface entirely free for the engagement therewith of the peripheries of a series of friction-rolls, as below described. The pivot-ring is thus rigidly fixed in a central position on the truck-frame.

To the frame-work of the car-floor (indicated by dotted lines in Fig. 1, and shown in section in Fig. 2) are rigidly bolted a series of metallic roller-supports, 9, within each of which a friction-roll, 10, is hung to rotate freely in a horizontal plane, and said rolls are so set that their peripheries have a free engagement with the outer side of said pivot-ring 8. The positions of said rolls 10 relative to said ring are clearly indicated in dotted lines in Fig. 1. A frictional bearing-wheel, 12, is hung in a suitable frame supported on the car-truck frame on the opposite sides of said pivot-ring 8, as shown in Figs. 1 and 2, said friction-wheels being so located that the timbers of the floor of the car 13 have a bearing thereon and the weight of the car is supported thereby. Said wheels 12 have a slight reciprocating rotary motion during the swinging movement of the car-truck under the car, while the latter is guided by the pivot-ring 8 and the friction-rolls 10, located outside of said ring.

Under each end of each of the frames 14, in which the aforesaid friction-wheels 12 are hung, is placed a spring, 15, (see Fig. 2,) whereby ease of motion is imparted to the car, which rests upon said wheels. The motion of the car, which is permitted by the said bearing-springs 15, causes a vertical motion to be imparted to the friction-rolls 10 opposite the adjoining side of the pivot-ring 8, and therefore said ring is supported by the clips 7, secured to the inner side of said ring, thereby leaving the outer side clear and un-

obstructed to permit said spring motion of the car without interfering with the mechanism which supports said pivot-ring.

What I claim as my invention is—

5 A car-truck having its pivot-ring rigidly secured to the truck-frame, combined with a car-body having its floor extending wholly over said ring, and a series of friction-rolls

hung to the under side of said floor to rotate in a horizontal plane with their peripheries ⁱⁿ opposite the outer side of said ring, substantially as set forth.

SUMNER A. BEMIS.
